(57) **CLAIM**

The ornamental design for a furniture article, as shown and described.

DESCRIPTION

FIG. 1 is an upper perspective view of the furniture article showing my design.

FIG. 2 is a front view thereof, rear and side views being identical;

FIG. 3 is a corner view thereof;

FIG. 4 is a top view thereof; and,

FIG. 5 is a bottom view thereof.

The broken lines shown in the figures show environmental features that form no part of the claimed design.
